UNITED STATES PATENT OFFICE.

MARIUS DUVALL, OF GOLDFIELD, NEVADA.

CARBURETER.

1,220,965.

Specification of Letters Patent. Patented Mar. 27, 1917.

Application filed March 31, 1916. Serial No. 88,065.

To all whom it may concern:

Be it known that I, MARIUS DUVALL, a citizen of the United States, residing at Goldfield, in the county of Esmeralda and State of Nevada, have invented new and useful Improvements in Carbureters, of which the following is a specification.

This invention relates to an improvement in carbureters for internal combustion engines.

Its principal object is to provide a carbureter of an exceedingly simple construction wherein adequate provision is made for accurately proportioning the constituents of the fuel mixture for any quantum delivered by the carbureter and for accurately adapting the quantum of the fuel mixture to the speed of the engine.

The invention consists in certain detail features of structure and combination which, together with the above and other objects and advantages will be set forth as the description proceeds.

An embodiment of the invention is illustrated in the accompanying drawing, wherein:

Figure 1 is a vertical central section of a carbureter in which the features of the invention are incorporated; and

Fig. 2 is an enlarged detail sectional view on the line 2—2 of Fig. 1.

Similar characters of reference designate corresponding parts in both of the views.

The carbureter consists of a carbureting chamber 1 which is arranged above and axially alines and communicates with an air pipe 2 open to the atmosphere at its lower end. The fuel pipe 3 is set co-axially within the pipe 2 and has at its upper end a spraying nozzle 4 which alines axially with the chamber 1. Adjacent the nozzle 4 the pipe 2 is formed with a Venturi-type choke rib 5 which provides a reduced, relatively narrow air throat-way 6 concentric to the nozzle 4. The latter has at its apex a constantly open fuel discharge bore 7 and suitably below its apex a series of laterally directed fuel discharge openings 8 which are preferably helically arranged.

The chamber 1 is, as usual, in line with the motor suction tube 9 to which the carbureter is suitably connected.

The regulation of the proportions of the air and fuel delivered to the mixing chamber and also of the quantum of the mixture

is controlled by a sleeve valve 10 which has a relatively close surrounding fit on the fuel pipe 3 and is movable lengthwise of said pipe. The valve 10 has at its upper end a circumscribing flange 11 which functions as an air valve and controls the efficient size of the air throat-way concentric to the pipe 3 and provided by the pipe 2. The width of the flange 11 is selected whereby when the sleeve 10 is in its uppermost position said flange will completely close the throat-way 6. In such a case communication will be had between the chamber 1 and the pipe 2 by means of openings 12 formed in the flange 11 and of which a suitable number are provided.

The openings 8 are arranged below the reduced throat-way 6 and the sleeve 10 has upward movement to diminish the number of openings 8 which participate in the discharge of fuel from the fuel pipe 3 and has downward movement to increase the number of such openings 8.

The carbureter is equipped with the usual butterfly throttle valve 13 which is arranged near the upper end of the mixing chamber. Preferably, the operations of the valve 10 are correlated to the operations of the throttle valve 13, and for this purpose, the valve 10 is provided with an upright bail 14 which is connected by a link 15 to the valve 13 in such manner that as the valve 13 is opened, the valve 10 is moved downward, and as the valve 13 is closed, the valve 10 is raised.

The drawings show the throttle valve 13 closed and the valve 10 in its uppermost position. In such position of the valve 10, the openings 8 are entirely covered and the throat-way 6 is closed, communication being provided between the mixing chamber 1 and the pipe 2 by the openings 12. The object of the provision of the single constantly open fuel discharge bore 7 and of the constantly open air passages 12 is to enable the engine to be run at low or "throttling" speed and, therefore, the throttle valve will have a certain very limited initial range of opening movement during which the sleeve 10 will not uncover the openings 8 and the flange 11 will not open the throat-way 6. When the throttle valve is thus very slightly opened, the engine may be run at its lowest or throttling speed.

The mixing of the fuel is obviously pro-

5 moted by the provision of the choke rib 5. As a further aid in effecting a good mixture of the air and gas, it is preferred to provide the pipe 3 with a helical rib 16 which extends toward the face of the pipe 2 and by which the air induced through the pipe 2 is given a whirling motion as it passes into the mixing chamber 1.

10 The fuel pipe 3 leads from a float feed chamber, as usual, and this chamber, indicated at 17, is preferably concentric to the pipe 2 and is removably secured to the upper casting of the carbureter with which the chamber 1 and the pipe 2 are formed. The 15 chamber 1 is preferably jacketed, as at 18, and the float feed chamber 17 is secured to the base of the jacket 18 by bolted flange connections 19 and has its bottom provided with an opening 20 through which the lower 20 end of the pipe 2 projects.

I claim—

1. In a carbureter, in combination, a carbureting chamber, an air pipe open to the lower end of said chamber, a fuel pipe arranged co-axially within the air pipe and having near its upper end laterally directed fuel discharge openings, the air pipe having a Venturi-type choke rib adjacent said spraying nozzle, and a valve concentric to the fuel pipe and slidably lengthwise thereof to control the said openings of the fuel pipe, the valve having a flange to control the air passage between said air pipe and said fuel pipe.
2. In a carbureter, in combination, a carbureting chamber, an air pipe open to the lower end of said chamber, a fuel pipe arranged co-axially within the air pipe and having its upper end formed as a spraying nozzle and provided with a plurality of laterally directed openings, the air pipe having a Venturi-type choke rib adjacent said spraying nozzle, and a sleeve valve slidably surrounding the fuel pipe to control the openings of the spraying nozzle, the valve having at its upper end a circum-

scribing flange to control the air passage between said air pipe and said fuel pipe.

3. In a carbureter, in combination, a carbureting chamber, an air pipe open to the lower end of said chamber, a fuel pipe arranged co-axially within the air pipe and having its upper end formed as a spraying nozzle and provided with laterally directed openings and with an axial bore, and a valve concentric to the fuel pipe and slidably lengthwise thereof to control said laterally directed openings, the valve having a flange to control the air passage between said air tube and said fuel pipe. 60

4. In a carbureter, in combination, a carbureting chamber, an air pipe open to the lower end of said chamber, a fuel pipe arranged co-axially within the air pipe and having its upper end formed as a spraying nozzle and provided with laterally directed openings and with an axial bore, and a sleeve valve slidably surrounding the fuel pipe to control the openings of the spraying nozzle, the valve having at its upper end a circumscribing flange to control the air passage between said air pipe and said fuel pipe. 65

5. In a carbureter, in combination, a carbureting chamber, an air tube open to the lower end of said chamber, a fuel pipe arranged co-axially within the air tube and having near its upper end laterally directed fuel discharge openings, and a sleeve valve slidably surrounding the fuel pipe to control the said openings of the fuel pipe, said valve being provided with a circumscribing flange controlling the air passage between said air tube and said fuel pipe. 75 80

In testimony whereof I have hereunto set my hand in presence of two subscribing witnesses.

MARIUS DUVAL.
